CHAIR

George W. Covington, Kansas City, Kans.

Application March 6, 1937, Serial No. 129,448

4 Claims. (Cl. 155—139)

This invention relates to chairs and more particularly to those of collapsible and adjustable type.

The principle object of the present invention is to provide a chair which simulates a saddle and which enhances the comfort of persons who have been horseback riding, together with the provision of adjustable features for the chair whereby the person using the chair may rest in an upright sitting position or reclining position.

Other objects of the present invention are to provide variously positioned foot-rests for the user of the chair and to make adequate provision for collapsing the chair in such a manner that it occupies a minimum amount of space for storage purposes.

In accomplishing these and other objects of the present invention, I have provided improved details of structure, the preferred form of which is illustrated in the accompanying drawing, wherein:

Fig. 1 is a perspective view of a chair embodying the features of the present invention, the chair being shown in substantially upright position.

Fig. 2 is a vertical cross-section through the hinge point of the chair seat on the line 2—2, Fig. 1.

Fig. 3 is a detail perspective view of the lower curved ends of the back-rest section support.

Fig. 4 is a fragmentary vertical cross-section on the line 4—4, Fig. 1, illustrating the mounting of the forward end of the seat on its support.

Fig. 5 is an elevational view of the chair illustrating same in reclining position, the upright position of the back-rest being shown in dotted lines.

Fig. 6 is a detail perspective view of the clamp for maintaining the back-rest in reclining position.

Referring more in detail to the drawing:

The invention consists generally of a frame 1 provided with a seat member 2, a back-rest member 3 and a foot-rest member 4.

The frame 1 preferably consists of a substantially U-shaped angle iron having a base 5 and arms 6 extending rearwardly from the base and having slightly bent outer ends 7. A cross piece 8 is provided at the outer ends of the arms and is mounted on the horizontal flanges 9 of the frame.

An additional cross piece 10 is mounted on the flange 9 substantially midway the length of the arms 6 and suitable braces 11 are mounted on the arms 6 and connected to the cross piece 10.

The seat member 2 preferably consists of a

substantially saddle-shaped portion having greater width at its rear end 12 than its forward end 13, the lower face of the rear end 12 being provided with bored bosses 14 for receiving a pivot rod 15 extending through the bosses and through the vertical flange 16 of the arms 6 for engagement in suitable holes in the flattened ends 17 of the crossed legs 18. The legs 18 are pivotally fixed at their cross points, as at 19, and a chain 20 or similar fastening device is suitably secured to the cross points 19 of the legs and to the cross piece 10 of the U-shaped frame for limiting outward pivotal movement of the legs 18 relative to the U-shaped frame 1 and seat 2.

The back-rest member 3 is mounted in a preferably U-shaped frame 21 having downwardly extending arms 22 and forwardly curved lower ends 23, as shown in Fig. 3.

The curved lower ends 23 are provided with slots 24 adapted for engagement over the ends of the pivot rod 15 between the seat bosses 14 and the frame 1 for slidably pivoting the back-rest member relative to the frame and seat member.

Pivottally mounted on the arms 6 of the frame 25 member 1 are connecting arms 25 having their ends suitably pivoted to the arms 6, as at 26, and their opposite ends provided with slots 27 engageable over lugs 28 mounted on the lower outer edges of the back-rest member 3 in such a manner that when the back-rest member 3 is in raised condition, as shown in dotted lines in Fig. 5, the arms 25 are engageable therewith for maintaining the back-rest in upright position, the arms 25 being removable from the back-rest member for engagement on the flange 9 in an out of the way position relative to the seat and back-rest members when the back-rest member is in reclining position, as shown in full lines in Fig. 5.

When the back-rest member is in reclining position, it is engageable with a pivoted clamp member 29, as shown in Fig. 6, which is pivotally mounted on the lower face of the flange 9 of the frame member 1 and which consists of a latch member 30 at one end of the clamp engageable over the flange 31 of the back-rest member frame 21 for maintaining the back-rest member in reclining position. A suitable hand-hold or levering device 32 is provided at the end of the clamp opposite the hook 30 for facilitating manipulation of the clamp.

The forward end 13 of the seat member 2 is mounted on a support 33 by means of a fastening device 34 suitably mounted in the seat member and extending through a horizontal footing por-

tion 35 of the support member 33. The support member 33 consists of a bent strip of sheet metal or the like which is looped as at 36 to provide the horizontal footing portion 35 and which has its 5 ends 37 extending outwardly relatively to the seat member in downwardly spaced relation thereto for forming foot-rest members 38 for the occupant of the chair, the ends of the foot-rest being turned downwardly as at 39 and suitably secured 10 as at 40 to the angled frame 1. Casters 41 are also provided on the frame 1 for facilitating maneuvering the chair to desired positions.

Mounted on the U-shaped frame member 1 substantially at the base thereof is a substantially 15 U-shaped foot-rest 42 having arms 43 fixed as at 40 to the frame member 1 and having support at 44 on the floor or the like. The connected ends 45 of the arms are curved upwardly to form a bearing for the legs 46 of the foot-rest 4 which 20 is mounted on a horizontal loop portion 47 of the foot-rest support 48, the support 48 being substantially similar to the support 33 previously described and having outwardly extending portions 49 and 50 to form foot-rest portions other 25 than the foot-rest 4 for an occupant of the chair.

The foot-rest support is preferably pivotally mounted on the arms 43, as at 51, additional holes 52 being provided in the arms to allow adjustment of the position of the foot-rest relative to 30 the seat member by moving the support to the other set of holes.

The operation of a chair constructed as described is as follows:

Assuming the chair to be in reclining condition, as shown in full lines in Fig. 5; when it is desired to adjust the chair to upright condition the finger portion of the clamp 29 is moved to the right, Fig. 6, to release the hook from engagement with the frame and back-rest angles 35 and the back-rest member 3 is merely lifted in such a manner that it pivots on the pivot rod 15 through engagement of the slotted ends 23 therewith, after which the arms 25 are engaged by their slotted upper ends with the lugs on the back-rest member 3.

It is apparent that the occupant of the chair may rest his feet in saddle fashion on the foot-rest 38 or he may stretch his legs for resting his feet on the foot-rest portions 49 and 50, or the 50 foot-rest member 4, such support for the occupant's feet being available when the chair is in reclining or upright position.

When the chair is to be collapsed the seat and the support are disconnected and folded onto the frame. The arms 25 are removed from engagement with the back-rest member 3 and pivoted forwardly for support on the flanges 9 of the frame member 1. The back-rest member 3 is moved forwardly relative to the seat member 2 and brought into engagement with the seat member. The foot-rest member 4 is pivoted rearwardly on the pivot points 40 and 51 for engagement over the upper rear face of the collapsed back-rest member 3 whereupon the legs 17 65 18 are pivoted forwardly on the pivot points 17 into engagement with the frame 1 to collapse the

chair into a condition which requires a minimum amount of storage space. The operation is reversible to change the chair from collapsed to extreme reclining position whereupon the clamp 29 is moved to the left, Fig. 6, to secure the flange 31 of the back-rest member in engagement with the flange 9 of the U-shaped frame member.

The principal advantages in a chair embodying the features of the present invention are that a novel chair is provided which is peculiarly 10 adapted for use by patrons of horseback riding academies and the like, which adds to the comfort of the patrons, and which is durable and easily collapsible when not desired for use.

What I claim and desire to secure by Letters 15 Patent is:

1. In a collapsible chair of the character described, an inclined frame having its front end resting on a floor, members pivotally mounted on the frame and supporting the rear end of the 20 frame, means limiting the spread of the pivoted members from the frame, a seat member having its rear end pivoted to the upper end of the frame, a seat support pivoted to the frame and detachably supporting the front end of the seat; said pivotal frame support comprising crossed leg members connected substantially at their mid-portions.

2. In a chair of the character described, a seat member having greater width at its rear end than at its front end, means supporting the rear end of the seat member, and means supporting the front end of the seat member, said last named means including a member having a loop at its upper end engaged with the bottom of the seat 35 member at the fore end thereof, and having legs at its lower end, and having outwardly extending foot rest members connecting the ends of said loop with said legs.

3. In a chair of the character described, a seat member having greater width at its rear end than at its front end, means supporting the rear end of the seat member, and means supporting the front end of the seat member, said last named means including a member having a loop at its 40 upper end engaged with the bottom of the seat member at the fore end thereof, and having legs at its lower end, and having outwardly extending foot rest members connecting the ends of said loop with said legs, said loop being detachably 45 connected with said seat member and said legs being pivotally engaged with the means supporting the rear end of the seat member for collapsing the chair at will.

4. In a chair comprising a seat member and 50 a frame supporting the seat member, means for supporting the feet of a person sitting in the chair including a pair of spaced legs engaged with the frame adjacent to the forward end of the chair and extending upwardly relative to the 55 frame, said legs being turned inwardly toward each other substantially midway their length to form foot rest members, said legs being turned upwardly at the inner ends of said foot rest members and terminating in a loop joining said legs. 60 65
